UNITED STATES PATENT OFFICE.

WILLIAM H. BEEHLER, OF BALTIMORE, MARYLAND.

NOTCH AND TIP CONSTRUCTION FOR UMBRELLAS AND PARASOLS.

1,096,216.

Specification of Letters Patent.

Patented May 12, 1914.

Application filed September 3, 1910. Serial No. 530,273.

To all whom it may concern:

Be it known that I, WILLIAM H. BEEHLER, a citizen of the United States, and resident of the city of Baltimore, in the State of Maryland, have invented certain new and useful Improvements in Notch and Tip Construction for Umbrellas and Parasols, (Case No. 10,) of which the following is a specification.

10 My invention relates to improvements in umbrella and parasol construction and particularly to an improved form of notch and means for securing it to the rod; also, to the combination with the notch of means for 15 securing a removable tip or ferrule end; also, to a novel form and arrangement of finishing cap employed in combination with the notch and removable tip.

The characteristics and advantages of the 20 invention will be further pointed out as far as is necessary in connection with a detailed description of the accompanying drawing which shows exemplifying structures embodying the invention.

25 Figure 1 is a longitudinal section of the outer end of the rod and the ferrule end; Fig. 2 is a view of my combined notch and dowel; Fig. 3 is a view similar to Fig. 1 showing a modified form of finishing cap. 30 Fig. 4 shows a modified arrangement of finishing cap. Fig. 5 shows another modified arrangement of finishing cap.

Referring first to Figs. 1 and 2, reference character 1 designates a tubular rod. At 35 the outer end of the rod is secured a fitting 2 which is my combined notch and dowel structure comprising a notch proper 3, a plain dowel 4, and a screw dowel 5. This notch structure is conveniently formed of a 40 single piece of metal. The plain dowel 4 is inserted in the rod and secured by a pin 6 or in any other suitable manner. The tubular tip 7 is internally threaded at its inner end to engage the screw dowel 5 and 45 the inner end of the tip is also flared as at 8 to form a graceful junction between the tip and the umbrella proper. This flared end may take the place of a finishing cap when no special cap is employed since when 50 the tip is screwed into position as shown in Fig. 1 the flared end will lap over the gathered end of the cover as it lies over the end of the notch.

To protect the end of the cover when the 55 tip is removed I usually provide an independent finishing cap 9 which is screwed on

the screw dowel 5 and permanently protects the gathered end portion of the cover.

To prevent loss of the tip when it is unscrewed a slider 10 having a head 11 is placed 60 within the tip. A link 12 pivotally connects the slider with the end of the screw dowel 5. A stop 13 which may be formed by punching in the metal of the tip limits the movement of the tip in relation to the slider. 65 Persons skilled in the art understand how the tip is secured in operative position as shown in Fig. 1 and how it is unscrewed and retained in loose connection with the rod when the umbrella is put in condition 70 for packing in a suitcase or trunk.

Fig. 3 shows a modified form of finishing cap 20 which is screwed on the screw dowel 5 and is provided with a tubular extension 21 which surrounds the inner end of the tip 75 when the latter is screwed home. This extension 21 of the finishing cap presents an attractive appearance when the tip is screwed into position and the tubular extension also very strongly braces the joint between the 80 tip and the umbrella proper.

Among the principal features of my invention as will be understood from the foregoing description, are the combined notch and dowel structure shown in Fig. 2; the 85 arrangement of this notch structure to receive a detachable tip; the provision of a finishing cap intermediate the tip and the notch proper; the arrangement of this finishing cap so that it remains in position to 90 protect the end of the cover when the tip is removed, and the provision of an extended sleeve on the finishing cap to reinforce the joint of the removable tip.

It has frequently been found that when 95 notches are secured to umbrella rods in the ordinary manner by pinning, the hole in the rod accommodating the pin is so near the end of the rod that after the umbrella has been put in use, the metal of the rod breaks 100 through, permitting the notch to become dislodged and practically ruining the umbrella. It will be observed that in the structures already described, the pin which secures the notched structure to the rod may be placed 105 practically any desired distance from the end of the rod and there is no possibility of the metal of the rod breaking through to the end of the rod to permit dislodgment of the pin or displacement of the notch.

Fig. 4 shows a modified construction which still enables the pin securing the notch to be

advantageously placed in a similar manner. The notch 30 is placed some distance from the end of the rod 1. A dowel 31 is inserted in the end of the rod and this dowel carries a screw extension 32 for attachment of the removable tip in an obvious manner. A pin 33 passes through the notch, rod and dowel 31 a considerable distance from the end of the rod so that there is no possibility of the splitting of the rod to permit dislocation of the pin. The extension 34 of the rod beyond the end of the notch permits screwing a finishing cap 35 permanently to the rod. In Fig. 5 a somewhat similar construction is shown in which the finishing cap 35^a is secured to the extended end 34 of the rod in any convenient way, for instance by a pin 36. The finishing cap has a tubular extension 37 protruding a considerable distance beyond the end of the rod and interiorly dimensioned so that it closely fits outside of the removable tip 7 when the latter is screwed into operative position. This extension 37 of the finishing cap thus provides a substantial reinforcement for the joint be-

tween the tip and the rod and greatly strengthens the frame structure at this point so that any bending cannot occur at the joint.

I claim:

In an umbrella or the like, the combination of a tubular metal rod, a tubular detachable tip screw-threaded in its open end, an integral notch structure comprising a notch proper, a solid rod at one side thereof rigidly fixed in the end of the rod, a screw-threaded member extending from the other side of the notch and detachably engaging the internal thread on the tip, a finishing cap screwed upon said screw-threaded member and against the notch proper and having a tubular extension to inclose the base of the tip, a slider within the tip, a stop to limit the outward movement of the tip when detached, and a link connecting the slider with the screw extension of the notch.

WILLIAM H. BEEHLER.
